(Cl. D57—1)

FIG. 1

The rear of the sunglasses frame not shown is plain and conventional.

The dominant features of my design reside in the portions shown in full lines.

I claim:

The ornamental design for a sunglasses frame or the like, substantially as shown and described.
